UNITED STATES PATENT OFFICE.

ERNST F. STECK, OF CHICAGO, ILLINOIS.

DESIGN FOR A WATER-TOWER FRAME.

SPECIFICATION forming part of Design No. 24,595, dated August 20, 1895.

Application filed November 22, 1893. Serial No. 491,682. Term of patent 14 years.

To all whom it may concern:

Be it known that I, ERNST F. STECK, a citizen of the United States, residing at Chicago, in the county of Cook and State of Illinois, 5 have invented and produced a new and original Design for Portable Water-Tower Frames, of which the following is a full, clear, and exact specification, reference being had to the accompanying drawings, showing a part thereof. 10 In the said drawings, Figure 1 is a side elevation of a water-tower frame, showing my design; and Fig. 2 is a plan view thereof, both of which figures are deemed essential to fully illustrate my design. 15 The leading features of my design consist of the side substantially horizontal pieces A, having a drop or countersink B formed therein. The forward ends of the side portions A are slightly higher than the rear ends of such 20 portions. The countersink or drop B is formed in the length of each of the said pieces A by giving such pieces the downbends F F',

the forward ones F of which downbends extend in an inclined direction from the forward ends of the pieces A, while the rear ones F' 25 are formed at a point substantially or near the mid-length of the pieces A, the two downbends F F' diverging upwardly from the portion B.

From the upper ends of the rear bends F' 30 the side pieces A extend rearwardly in a substantially horizontal direction, and such rear portions are bridged by a platform or flat surface C, having an oblong cut-away portion C' in its forward end, while the drops or countersinks B of the two side frames are crossed by oppositely-curved bars D E.

What I claim is—

The design for portable water tower frames, substantially as herein shown and described. 40
ERNST F. STECK.
